UNITED STATES PATENT OFFICE.

ROBERT M. KEATING, OF SPRINGFIELD, MASSACHUSETTS.

SPROCKET-CHAIN.

SPECIFICATION forming part of Letters Patent No. 619,315, dated February 14, 1899.

Application filed February 27, 1897. Serial No. 625,288. (No model.)

To all whom it may concern:

Be it known that I, ROBERT M. KEATING, a citizen of the United States of America, residing in Springfield, in the county of Hampden and State of Massachusetts, have invented new and useful Improvements in Sprocket-Chains, of which the following is a specification, reference being had to the accompanying drawings and letters of reference marked thereon.

In the drawings like letters of reference indicate like parts.

Figure 1 is a side view of my improved device. Fig. 2 is a plan view of the same with a part in section. Fig. 3 is a side and edge view of one of the outer links, a part of the edge view being in section. Fig. 4 is an inner face and edge view of one of the inner links with a part of the edge view in section; and Fig. 5 is an enlarged view of the several parts, showing their construction and arrangement and relation to each other, a part of the antifriction-roll and collar or bushing being broken away and a part of two links being shown in section.

In detail, *a* indicates the inner links. *b* indicates the outer links; *c*, the pivots or rivets; *d*, antifriction-rolls; *e*, collars or sleeves, and *f* recesses in the inner face of the inner links to receive the ends of the collars or sleeves.

The object of my invention is to provide an improved construction of sprocket-chain wherein friction will be avoided and a rolling contact between the sprocket-wheel and engaging parts of the chain is produced and wherein the wear of the antifriction-rolls upon their supports will be reduced to a minimum and wherein the parts subjected to the greatest wear may be hardened without also hardening parts of the device which it is found objectionable to harden and to provide a construction wherein the wear is extended over a large area and generally to improve the construction of sprocket-chains.

My invention consists in the construction and arrangement as herein set out, whereby the objects of my invention are attained.

The construction of my device will be readily understood on reference to the drawings, wherein I show a series of inner links *a*, provided near each end with rivet or pivot openings and with recesses *f*, into which the ends

of the collars or sleeves *e* fit. The antifriction-rolls *d* are mounted upon the collars or sleeves *e*, and the rivets or pivot-pins *c* are of a size at their body or intermediate portion to fit the openings in the sleeves and the openings in the inner links, and at their ends are of less diameter than their body portion and pass through suitable openings in the outer links *b*, the shoulders of the pins bearing against the inner face of the outer links, so that when the ends of the rivets or pins *c* are upset all danger of binding the antifriction-wheels between the side walls of the inner links is avoided.

It will be seen that the collars or sleeves *e* rest within the recesses *f* in the inner face of the inner links and bear with their ends in the bottom of these recesses. It will now be observed that the sleeves or collars and antifriction-rolls may be made of any desired material and may be hardened, so that the parts subjected to the greatest wear will be hard, while the parts subjected to the least wear and found most difficult to harden may be of soft material.

In assembling the parts the ends of the rivets or pivot-pins are turned over and upset, so as to firmly bind the outer links between the shoulders on the pivots and the upset ends, so that the outer links on both sides are firmly united and neither will turn on the pivots. The inner links are united in a similarly rigid manner by the sleeves or collars *e*, the ends of which have a driving fit in the recesses *f*. The surfaces subjected to wear, therefore, are not those between the pivot-openings in the links and the pivots, but between the bodies of the pivots and the sleeves or collars *e*.

The inner links are of sufficient length so that when the antifriction-rolls are mounted in the end portions thereof the space between the rolls so mounted and the inner faces of the links forms an opening of the proper dimension for a tooth upon the sprocket-wheel, and the tooth will have a rolling contact throughout its whole extent of bearing-surface, while as heretofore constructed in sprocket-chains, especially those made up of straight links, the openings for the teeth of the sprocket-wheel have been formed between the ends of adjacent inner links and the cen-

tral portions of the outer links, so that if the sprocket-wheel tooth had sufficient width to substantially fill the opening between the inner faces of the outer links the surface of the 5 teeth against a rolling-contact bearing is reduced to the extent of the thickness of the two inner links unless some means were provided for maintaining the chain in proper alinement other than contact with the teeth, 10 and by this construction also I am enabled to arrange the ends of each pair of inner links closely adjacent to the next pair, so that the space between the teeth on the sprocket-wheel will be filled by the two antifriction- 15 rolls mounted in opposite ends of adjacent sets of inner links.

It will be observed that the seating of the ends of the bushings in the inner links instead of allowing the same to pass through 20 these links avoids all danger of the inner links being forced toward each other, and thus binding the antifriction-rolls, and also avoids danger of throwing the chain out of accurate alinement.

25 Having therefore described my invention,

what I claim, and desire to secure by Letters Patent, is—

1. In a sprocket-chain the combination of inner links having pivot-openings, a portion of each of which is of an enlarged diameter, 30 outer links having openings of less diameter, pivots having their end portions of a size to fit the pivot-openings in the outer links, and the intermediate portion of a diameter to fit the pivot-opening in the inner links, sleeves 35 mounted on the pivots and arranged with their ends entering the enlarged portions in the inner links, and antifriction-rolls mounted on the sleeves substantially as shown.

2. The combination in a sprocket-chain of 40 inner and outer links, having recesses on their inner faces, pivots passing through said links, sleeves on said pivots with their ends entering said recesses in the inner links, and friction-rolls mounted on said sleeves, substantially 45 as shown and described.

ROBERT M. KEATING.
